(Cl. D26—5)

FIG. 1.

FIG. 2.

FIG. 3.

FIG. 1 is a view, in perspective, of an ion generator showing our new design;

FIG. 2 is a side elevational view on a slightly reduced scale; and

FIG. 3 is a rear elevational view on the same scale as FIGURE 2.

The dominant features of our design reside in the portions shown in full lines.

The bracket and base plate have been omitted from FIGS. 2 and 3 for convenience of illustration.

We claim:

The ornamental design for an ion generator substantially, as shown and described.
